By his Attorney, Jno. D. Cole

UNITED STATES PATENT OFFICE.

WALTER CHARLES DUFEU, OF CHILlicothe, OHIO.

TOWEL OR NAPKIN HOLDER.

SPECIFICATION forming part of Letters Patent No. 356,225, dated January 18, 1887.

Application filed June 1, 1886. Serial No. 203,767. (No model.)

To all whom it may concern:

Be it known that I, WALTER CHARLES DUFEU, a citizen of the United States, residing at Chillicothe, in the county of Ross and State 5 of Ohio, have invented certain new and useful Improvements in Towel or Napkin Holders; and I do hereby declare the following to be a full, clear, and exact description of the invention, such as will enable others skilled in the 10 art to which it appertains to make and use the same.

My invention relates to certain new and useful improvements in towel and napkin holders, and is designed to afford a secure fastening for 15 the fabric to the sustaining device without danger of tearing said fabric. For the attainment of this purpose I have devised the construction illustrated in the accompanying drawings, wherein—

20 Figure 1 is a perspective view of one form of my improved holder in an open position. Fig. 2 is a like view of a modification of the same. Fig. 3 is a like view of a further modification. Fig. 4 is a side view of Fig. 1. Fig. 25 5 is a side view of Fig. 2; and Fig. 6 is a longitudinal section of Fig. 3 upon the line 6 6.

Similar letters of reference indicate similar parts throughout the several views.

Referring more particularly to Figs. 1 and 30 4, A indicates a strip of metal perforated at one end for the reception of a fastening eye-screw, B, and provided at its other end with the terminal wedge-ball C, also of metal.

D indicates a piece of spring metal, rounded 35 or looped at E, where it has an internal diameter slightly larger than the external diameter of the ball C, so as to admit of the fabric of the towel, napkin, or similar article to be clamped between the opposite surfaces of the 40 two. A rivet, F, unites the piece A with the spring D and forms a pivotal point upon which the tongue-piece A turns.

It will be observed that the distance between 45 the two parallel portions of the spring, when the device is in the open position, is less at the point G than at the point H. As a result of this construction, when the piece A is revolved to the closed position, as shown in Fig. 4, the tendency of the spring D is to retain it 50 in such position, as considerable pressure is exerted against it at the point G. In Figs. 2

and 5 the construction is varied by carrying outward the two ends of the piece D', perforating them at their outer ends for the reception of the eye-screw B'. In Figs. 3 and 6 the 55 eye-piece passes through both the spring D² and the intermediate piece, A².

It will also be observed that for greater security indentations H' are made in opposite sides of the piece A², and corresponding projections, L', fitting therein, are made in the inner sides of the spring D².

The operation of my invention will be readily understood. The edge of the towel, napkin, or other fabric to be held is placed 65 across the loop E and the ball C is then forced inwardly over said fabric, pressing it into the loop E and clamping and fastening it therein between the inner surface of said loop E and the outer surface of the ball C. This wedge- 70 pressure is sufficient to retain the fabric in position against ordinary pulling strains, whereas it may be readily disengaged by pressing the ball C in the opposite direction.

It is evident that the terminal projection of 75 the tongue-piece A may be a wedge of other shape than the spherical one shown in the drawings, so long as it exerts a clamping action upon the interior surface of the loop. The interior surface of the loop should corre- 80 spond, however, in general outline with that of the wedge.

Having thus described my invention, what I claim, and desire to secure by Letters Patent, 85 is—

1. A towel or napkin holder consisting of a piece of metal bent to form a loop, and a tongue pivoted thereto and provided at its free end with a ball or wedge, substantially as described.

2. A towel or napkin holder consisting of a piece of metal provided with a looped portion and two parallel sides, and a tongue provided at its free end with a ball or wedge and pivoted between the said sides, substantially 95 as described.

In testimony whereof I affix my signature in presence of two witnesses.

WALTER CHARLES DUFEU.
